PUMP

Filed Dec. 19, 1927

Inventor
F. Rahm.

By his Attorney *J. Joffe*

UNITED STATES PATENT OFFICE

FREDERICH RAHM, OF LOUISVILLE, KENTUCKY, ASSIGNOR TO PRECISION SYRUP PUMP COMPANY, OF LOUISVILLE, KENTUCKY, A CORPORATION OF DELAWARE

PUMP

Application filed December 19, 1927. Serial No. 240,985.

My invention relates to pumps for dispensing a predetermined quantity of liquid, and it is of the type known as syrup pumps for soda fountains.

5 The object of my invention is to provide a pump which will deliver a definite charge, whether the pump is operated frequently or whether the charge is dispensed after a lapse of a few hours.

10 Another object of the invention is to provide a pump which will minimize the delivery of froth, and compensate for irregularities in working parts, generally present in the containers from which the pump delivers.

15 A still further object of the invention is to provide a pump of the character described, in which the quantity to be discharged by the pump can be adjusted by changing the setting without in any way affecting the piston displacement.

20 In the appended drawing forming part of this application, Figure 1 is a vertical section on line 1—1, Figure 3 of a pump embodying my invention.

25 Figure 2 is a similar section on line 2—2, Figure 3, the upper portion of the pump not being shown.

Figure 3 is a section on line 3—3, Figure 1.

30 Figure 4 is a plan view of the cylinder and the valve housings, and Figure 5 is a section through the valve housings of the cylinders on line 5—5, Figure 3, the valves being eliminated from the drawing to better illustrate the structure.

35 Referring to the drawing, 10 is the cylinder open at the bottom. A piston 11 fitting into the cylinder has its piston rod 12 projecting through the cylinder top and extending into the socket 13 of a header 14. Secured to the piston rod 12 is a button 15 which has a sleeve 16 extending into the socket 13 of the header. A spring 17 housed in the sleeve and socket maintains the piston 11 normally against the top of the cylinder, as shown in dash and dot lines in Figures 1 and 2.

40 The header 14 is provided with a spout 18 connected by a tube 19 to the valve housing 20, wherein a check valve 21 below the tube

19 checks the flow from the spout past the valve.

45 The valve housing 20 has also a bore 22 which is coaxial with a bore 23 and a bore 24, the bore 24 being larger than 23 and the bore 23 being larger than 22. The bore 22 has a port 25 leading below the check valve 21. The bore 23 has a port 26 leading to the top of the cylinder. A plunger 27 is located in the bore 22. It has a reduced portion 28 which terminates with a plunger 29 that fits the bore 23. A spring 30 is provided on the reduced portion 28 between the plunger 29 and the shoulder 31 formed by the bores 22 and 23. This spring normally tends to 55 move the plunger 29 out of the bore 23 and maintain the port 25 closed.

60 The plunger 27 is adjustably threaded to a head 32 which limits the motion of the plungers 27 and 29 by the spring 30. The head 32 carries a trigger 33 which is engageable by a pawl 34 secured to the piston rod 12 to engage the trigger when the piston is at the end of the suction stroke, which is limited by the stop collar 35 secured to the 65 rod 12. The pawl 34 is maintained in alignment with the trigger by a guiding groove 36 provided in the stay rod 37 which connects the header to the cylinder.

70 When a charge is to be delivered by the pump, pressure is applied to the button 15 and the same is moved from the dot and dash position in Figure 1 to the full line position in the same figure, the downward motion of the piston being limited by the stop collar 35. The same motion will cause the pawl 34 to engage the trigger 33. During the downward displacement of the piston, a charge will be taken in through the bores 24 and 23 and port 26. As the piston 75 returns under the influence of the spring 17, the pawl 34 will carry therewith the trigger 33 and therefore the plungers 27 and 29 compressing the spring 30. It is evident that the spring 17 is stronger than the 80 spring 30.

85 Until the plunger 29 engages the bore 23, there will be a discharge from the cylinder through the bores 23 and 24 back into the container from which the charge has been 90 95 100

taken. By the time the plunger 29 engages the bore 23, the plunger 27 starts to uncover the port 25, thereby causing the remainder of the charge to pass toward the spout 5 through the check valve 21.

By permitting a partial return or waste of the charge to the container, most of the froth that has been taken in is returned to the container and only the liquid which 10 forms the remaining part of the charge in the cylinder is delivered through the spout. As the piston reaches the top of the cylinder, the trigger 33 is actuated by the projection 38 provided on the valve housing 15 to disengage the same from the pawl 34. This is shown in dot and dash lines of Figure 2. Thus the spring 30 is free to restore the plungers to their normal position; that is to say, the pump is ready for delivering 20 another charge.

In view of the character of the liquid for which these pumps are used, it is of advantage to provide in the cylinder annular grooves 37' at suitable intervals, as they 25 help to seal the clearance between the piston and the cylinder walls and therefore the seepage during the movement of the piston. For the same purpose, a groove 38' is provided in the bore 22 to prevent the liquid 30 stored between the check valve and the plunger 27 from seeping back into the container from which the charges are taken.

I claim:

1. In a pump for delivering a predetermined charge through a passage, means for accumulating a charge larger than the one to be delivered, and means in the passage for returning part of said charge at the beginning of the delivery only.

2. In a pump for delivering from a suitable source a predetermined charge through a passage, means for accumulating a charge larger than the one to be delivered, and means in the passage for returning part of said charge during the delivery back to the source.

3. In a pump for delivering from a suitable source a predetermined charge through a passage, means for accumulating a charge larger than the one to be delivered, means in the passage for returning part of said charge during the delivery and adjustable means for varying the amount to be returned.

4. In a pump, a cylinder, a spring actuated piston therein, means for returning a part of the charge delivered by the piston, and means for actuating said return controlling means during the delivery stroke of the piston.

5. In a pump, a cylinder, a spring actuated piston therein, a spout leading from the cylinder, a spring actuated plunger valve interposed between the spout and the cylinder and normally closing the passage from the cylinder to the spout, a second plunger valve

cooperating with the first for controlling the intake of the cylinder and normally maintaining the intake open, means for actuating the plunger valve during the discharge stroke of the piston, said second 70 plunger maintaining the intake open for a predetermined portion of the piston discharge stroke and said first plunger maintaining the discharge closed for substantially the same period.

6. In a pump, a cylinder, a spring actuated piston therein, a spout leading from the cylinder, a spring actuated plunger valve interposed between the spout and the cylinder and normally closing the passage from the cylinder to the spout, a second plunger valve 80 cooperating with the first for controlling the intake of the cylinder and normally maintaining the intake open, a trigger connected to the plunger valves, a pawl movable with the piston for engaging the trigger at the end of the suction stroke, and means for releasing the trigger from the pawl at the end of the discharge stroke, said second plunger 90 maintaining the intake open for a predetermined portion of the piston discharge stroke, and said first plunger maintaining the discharge closed for substantially the same period.

7. In a pump, a cylinder, a spring actuated piston therein, a spout leading from the cylinder, a valve checking the flow from the spout, a spring actuated plunger valve interposed between the check valve and the cylinder and normally closing the passage from the cylinder to the check valve, a second plunger valve 100 cooperating with the first for controlling the intake of the cylinder and normally maintaining the same open, a trigger connected to said plunger valves, a pawl movable with the piston for engaging the trigger at the end of the suction stroke, means for releasing the trigger from the pawl at the end of the discharge stroke, said second plunger 105 maintaining the intake open for a predetermined portion of the piston discharge stroke and said first plunger maintaining the discharge closed for substantially the same period, and means for adjusting the plunger valves to vary the time of the operation with reference to the piston discharge 110 stroke.

8. In a pump, a cylinder, a spring actuated piston therein, said cylinder having a passage serving as an intake from a source and a discharge for the pump, means in said passage making it either an intake or a discharge passage, said means being arranged to return a part of the charge in the cylinder to the source, at the beginning of the delivery stroke of the piston.

FREDERICH RAHM.
